UNITED STATES PATENT OFFICE.

MAX SCHNEFEL, OF NEWARK, NEW JERSEY.

DESIGN FOR A NAIL FILE OR SIMILAR ARTICLE.

Application filed February 9, 1921. Serial No. 443,713. Term of patent 7 years.

To all whom it may concern:

Be it known that I, MAX SCHNEFEL, a citizen of the United States, residing at Newark, in the county of Essex and State of New Jersey, have invented a new, original, and ornamental Design for a Nail File or Similar Article, of which the following is a specification, reference being had to the accompanying drawings, forming a part thereof.

Fig. 1 is a side elevation and Fig. 2 an edge elevation of a nail file or similar article, showing my new design.

I claim:—

The ornamental design for a nail file or similar article, as shown.

MAX SCHNEFEL.
